INVENTOR

Wm. A. Frederick
BY
C. M. Fairbank
ATTORNEY

UNITED STATES PATENT OFFICE.

WILLIAM A. FREDERICK, OF BOSTON, MASSACHUSETTS, ASSIGNOR TO THE MOTOR CAR EQUIPMENT COMPANY, OF NEW YORK, N. Y., A CORPORATION OF NEW YORK.

AUTOMATIC OILER

1,255,088.

Specification of Letters Patent. Patented Jan. 29, 1918.

Continuation of application Serial No. 126,415, filed October 18, 1916. This application filed September 25, 1917. Serial No. 183,094.

To all whom it may concern:

Be it known that I, WILLIAM A. FREDERICK, a citizen of the United States, and resident of Boston, in the county of Suffolk 5 and State of Massachusetts, have invented certain new and useful Improvements in Automatic Oilers, of which the following is a specification.

This invention is an improvement in automatic oilers of the type shown and generally claimed in my copending application Serial No. 177,119, filed June 26th, 1917, and which utilizes the vibration, jarring or other usually slight bodily movement of the 15 machines or apparatus to be oiled, to effect the movement of an oil carrier from a source of supply to an oil delivery means.

In the specific form shown in said application, a wick or other capillary device raises 20 oil from a cup or reservoir and a ball above the oil level moves back and forth, by the jarring of the machine, over the upper open end of a centrally disposed delivery tube and into and out of engagement with said 25 capillary device to transfer successive small quantities of oil from said device to a position from which they may drain by gravity through said tube.

My present invention contemplates the use 30 of a wick or other capillary device to receive oil from said oil carrier and which thereby permits of the lateral as well as the downward delivery of oil. It also involves a 35 novel form of support for the oil carrier and certain other features.

With these and other objects in view the improved invention consists in the construction and combination of parts substantially as hereinafter described.

40 Of the accompanying drawings Figure 1 represents a vertical section through my improved automatic oiler in one of its embodiments.

Fig. 2 is a plan view of the same with 45 the stopper or cap removed, and with the duct nipple in section.

Fig. 3 represents a section on line 3—3 of Fig. 1.

Figs. 4 and 5 are vertical sectional representations of another embodiment of my invention, the section of Fig. 5 being at a right angle to that of Fig. 4 and

Fig. 6 is a vertical sectional representation of another modification.

Similar reference characters indicate the same or similar parts in all of the views.

Referring first to Figs. 1, 2 and 3, the reservoir 10 for the oil, is provided with a suitable cap or stopper 11, which may be screw-threaded or otherwise secured in place. Extending transversely of the reservoir 10, near its upper end, is a trough-shaped guide 12 for an oil-carrying vibrator 13, which is illustrated as a sphere, but obviously might be a short cylinder if the guide were properly shaped.

A wick 14 extends through an opening 15 at one end of the guide 12, down into the oil in the reservoir 10. Another wick 16 extends over the other end of the guide 12 70 out through a duct in the nipple 17.

It will readily be understood that by capillary attraction oil from the reservoir 10 has a constant tendency to reach the upper end of the wick 14. When the machine in which the oiler is attached is in motion, the vibrations of the machine cause the vibrator 13 to travel back and forth along the guide 12, and so take oil from the upper end of the wick 14, and transfer it to the wick 16, 80 which will conduct oil to the oil particular place to be lubricated. When the machine is idle or stationary and the parts are requiring no lubrication, the vibrator 13 will cease to move and therefore there will be no 85 oil conducted or transferred from one wick to the other.

A small hole 18 in the guide 17 serves to permit any accumulation of oil on or in the guide to return to the bottom of the reservoir.

In Figs. 4 and 5 I illustrate an embodiment of the invention designed to supply lubricating oil through a vertical nipple instead of a horizontal one. In said figures 95 the numerals which are the same as those

in Figs. 1, 2 and 3, indicate substantially the same features or parts. In said Figs. 4 and 5, the wick for conducting the outgoing oil is indicated at 16^a, and is inclosed 5 in a small tube 19, which communicates with a port 20 in the base of the reservoir, the latter communicating with a port 21 in the vertical nipple 17^a. With this form the vibrator 13 operates in the same manner as 10 hereinbefore described in connection with Fig. 1, to transfer oil from the upper end of the capillary wick 14 to the end of the outgoing conducting wick 16^a.

In Fig. 6 the reservoir 10^b having a cap 15 11^b, is provided with a nipple 22 having a port 23, the inner end of which is preferably larger than the outer end, to accommodate the inner end of the light link 24 which is pivoted at 25 in the enlarged end of port 20 23, so as to vibrate, the other end of the link 27 being pivotally connected at 26 to a float 27 which serves to support the vibrator 24 above the normal level of oil, a wick 28 is 25 connected in any suitable manner so that one end will move or rise and fall with the vibrator, the other end of the wick extending through the port 23. When the machine is in operation, vibration of the link 24 and float 27 will cause the float to effect more 30 or less splashing of the oil in reservoir 10^b and some of the oil will be thereby dashed onto the vibrator and its wick 28 and then by capillary attraction feed to the place needing lubrication. The only reason for 35 having the wick 28 extend so far down as shown in Fig. 6 is to increase the amount of oil that will be carried up by capillary attraction. The vibrator 24 alone would serve for some purposes, as even a metal link will 40 transmit some oil. By extending the wick 28 well down and nearly to the float to catch some of the oil splashed by the float, there will be a greater amount of oil supplied, as above stated.

45 This application is a substitute for and continuation of my prior application Serial No. 126,415, filed October 18th, 1916.

Having now described my invention, I claim:

50 1. An automatic oiler having a reservoir provided with an outflow duct, a wick in said duct, a guide adjacent the inner end of the duct, a wick having its upper end adjacent the other end of the guide, and a roller on 55 said guide and free to be vibrated back and forth between the said wicks.

2. An automatic oiler comprising a reservoir having a horizontal guide in its upper portion, a wick leading from the reservoir to one end of the guide, an outflow wick leading 60 from the other end of the guide, and a roller free to vibrate on the guide between the wicks.

3. An automatic oiler having a reservoir provided with an outflow duct leading from 65 its upper portion whereby oil in the lower portion of the reservoir cannot escape through said duct under normal stationary conditions, a wick for transmitting oil through said duct by capillary attraction, 70 said wick being above the normal level of oil in the reservoir, a vibrator free to be moved by the jarring resulting from the operation of the machine carrying the oiler, means for supporting the vibrator above 75 said normal level of oil, and means for supplying limited quantities of oil to said vibrator for transmission by the vibrator to the wick.

4. An automatic oiler having a reservoir 80 and two spaced wicks, one of said wicks being in position to take oil direct from the supply in the reservoir and the other wick being elevated and in position to deliver oil, and a vibrator operated solely by the bodily movement of the oiler to transfer oil 85 from one wick to the other.

5. An automatic oiler having a reservoir, a nipple extending laterally from one side thereof and adapted to be secured to a part 90 to which oil is to be delivered, said nipple having a passage therethrough, a guide extending transversely of the reservoir opposite the inner end of said nipple, a capillary device for raising oil from the lower portion 95 of said reservoir to the level of said guide, and a carrier movable back and forth along said guide from said capillary device to said passage.

6. An automatic oiler having a reservoir, 100 a nipple extending laterally from one side thereof and adapted to be secured to a part to which oil is to be delivered, said nipple having a passage therethrough, a guide extending transversely of the reservoir opposite the inner end of said nipple, a capillary device for raising oil from the lower portion 105 of said reservoir to the level of said guide, and a carrier movable back and forth along said guide from said capillary device 110 to said passage, the movement of said guide being due solely to the bodily movement of said oiler and the part to which it is attached.

7. An automatic oiler having a reservoir, 11 a horizontal guide therein above the normal level of the oil, a member mounted to roll back and forth along said guide upon the comparatively slight jarring or shaking of said reservoir, an outlet passage at one end 12 of said guide, and a capillary member for conducting oil upwardly from the lower portion of said reservoir to the opposite end of said guide.

8. An automatic oiler having a reservoir 12 adapted to be secured to a mechanism to be

oiled and thereby subjected to the jarring vibration or other similar movement of such mechanism, a pair of wicks, one leading from the oil to a point above the normal liquid level and the other leading to the exterior of said reservoir from a point above said level, and a vibrator operating to transfer oil from one wick to the other, the move-

ment of said vibrator being imparted thereto solely by the bodily movement of said mechanism.

Signed at Boston, in the county of Suffolk and State of Massachusetts this eighteenth day of September, A. D. 1917.

WILLIAM A. FREDERICK.
